[54] COMPASS HEADING DISPLAY

[75] Inventors: Charles R. Wesner, Crozet; Gregory Schluge, Afton, both of Va.

[73] Assignee: Sperry Corporation, New York, N.Y.

[] Term: 14 Years

[21] Appl. No.: 316,588

[22] Filed: Oct. 30, 1981

[51] Int. Cl. .... D10—04

[52] U.S. Cl. D10/74; D10/65;
D10/67; D10/68[58] Field of Search D10/65, 67, 68, 74;
116/298, DIG. 43, 202; 33/363 R;
340/753-754; 368/82, 239

[56] References Cited

U.S. PATENT DOCUMENTS

D. 135,533 4/1943 Braddon ..... D10/67 X
D. 139,426 11/1944 Heintz D10/67
D. 250,097 10/1978 Hendershot D10/65

D. 257,832	1/1981	Flint	D10/67
D. 259,924	7/1981	Bergkvist	D10/65
3,525,091	8/1970	Lally	340/753
3,609,750	9/1971	Budd	340/753
3,689,835	9/1972	Bickford	340/753 X
3,726,250	4/1973	Merk	340/754 X

OTHER PUBLICATIONS

Popular Mechanics—11/78—p. 38—Compass at bottom right.Primary Examiner—Nelson C. Holtje
Attorney, Agent, or Firm—Howard P. Terry

[57] CLAIM

The ornamental design for a compass heading display, as shown and described.

DESCRIPTION

FIG. 1 is a front elevational view of a compass heading display showing our new design;

FIG. 2 is a right side elevational view thereof, the left side being a mirror image thereto.

The top, bottom, and rear of the display are substantially flat, plain and unornamented.

FIG. 2.

FIG. 1.